H. F. LAFORTUNE

SPRING WINDING DEVICE

Filed Jan. 10, 1923

By *Watson E. Coleman*
Attorney

UNITED STATES PATENT OFFICE.

HENRY F. LAFORTUNE, OF BIDDEFORD, MAINE.

SPRING-WINDING DEVICE.

Application filed January 10, 1922. Serial No. 611,744.

To all whom it may concern:

Be it known that I, HENRY F. LAFORTUNE, a citizen of the United States, residing at Biddeford, in the county of York and State of Maine, have invented certain new and useful Improvements in Spring-Winding Devices, of which the following is a specification, reference being had to the accompanying drawings.

10 This invention relates to spring winding devices, and has for its object to provide a device of this character capable of being supported in a vise for easily and quickly winding a spring.

15 It is another object of the invention to provide a device of this character wherein springs of various widths may be evenly wound and readily removed.

20 It is a further object of the invention to provide a device of this character wherein the means for guiding and guarding the spring is adjustable according to the width of the spring.

25 It is a still further object of the invention to provide a device of this character wherein means are provided for holding the spring wound to permit the same to be removed from the winding device.

30 With these and other objects in view, the invention consists in the improved construction and arrangement of parts to be herein-after more particularly described, fully claimed and illustrated in the accompanying drawings, in which:—

35 Figure 1 is a view in elevation of a spring winder constructed in accordance with an embodiment of the invention;

Figure 2 is a view in elevation with the guard plate extended to one side;

40 Figure 3 is a transverse sectional view; and

Figure 4 is a view of a spring showing the clip applied.

45 Referring to the drawings, 5 designates a supporting plate having a shaft 6 rotatably mounted therein, the shaft being provided with a ratchet wheel 7. Secured to the supporting plate is a frame 8 having spacing blocks 9 projecting therefrom and adapted to engage the plate 5. This frame substantially coacts with the plate to provide a compartment for the reception of a pawl 10, a spring 11 being connected to the frame and the pawl for urging the pawl into engagement with the ratchet.

55 Projecting from one edge of the plate is

an extension 12 adapted to be disposed between the jaws of a vise or like holding means whereby the supporting plate may be supported in a convenient position for winding the spring. 60

Secured to one end of the shaft 6 is an operating handle 13, said handle projecting from the side of the plate remote from the frame 8. Projecting from the plate adjacent the frame is a shaft 14. A guard plate 15 is carried by the shaft, said guard plate having a slot 16 which extends to the central portion thereof. The guard plate is also provided with an extension 17 having a collar 18 adapted to receive the shaft 14. Secured to the supporting plate adjacent the shaft 14 is a keeper member 19, said keeper member having a plurality of recesses 20 adapted to receive the extension of the guard plate 15 so as to hold said plate in various adjusted positions on the shaft 14. 70

Carried by the plate 15 adjacent the shaft 14 is a supporting shaft 21 adapted to receive one end of a spring A, the opposite end of the spring being connected to the shaft 6. Projecting from the plate adjacent the shaft 21 is a guard shaft 22, adapted to prevent movement of the spring beyond the opposite edge of the supporting plate. The shaft 22 is provided with a lug 22^a adapted for engagement in the slots of spring ends so that springs having this type of end may be held against movement. 80 85 90

In the operation of the device, when it is desired to wind a spring the loop of the spring is engaged with the shaft 21 and the inner end of the spring secured to the shaft 6. The handle member is then rotated by the operator so as to cause the spring to be wound to the point desired during which time the pawl 10 engages the ratchet wheel in the usual manner to control the movement of the shaft. After the spring has been positioned on the shaft the guard plate 15 is rotated so as to permit the end of the shaft 6 to enter the slot 16, the guard plate being moved longitudinally of the shaft 14 according to the thickness of the spring. In this way the coils of the spring are disposed in the same plane and properly wound. After the spring has been wound to the extent desired a C-shaped clip 23 is engaged with the wound portions of the spring, the spring being wound to such a point that it is smaller in diameter than the 100 105 110

clip. After the clip is applied the spring is slightly unwound to permit the same to bind within the clip, whereupon the guard plate 15 may be removed and the spring disengaged from the shaft 6.

From the foregoing it will be readily seen that this invention provides a novel form of spring winding device capable of winding a spring of any width and wherein the spring may be readily removed from the device after winding without danger of unwinding and in such a position that it may be readily inserted in the mechanism of a clock in view of the novel C-shaped clip. In addition to this the extension 12 of the support permits the device to be secured in a vise or like holding member without requiring any special holding means.

What is claimed is:—

- 20 1. A spring winding device comprising a support provided with means for engagement within a vise to effect holding, a shaft journaled through said support and having a crank handle, a disk on the shaft spaced from the support and defining a compartment, a ratchet on said shaft within said compartment, a pawl within said compartment co-operating with said ratchet and having an end projecting beyond the support to facilitate manipulation, a guard plate rotatably mounted on said support and having a slot for the reception of said shaft, and means on the support for holding the guard plate in an adjusted position.
- 25 2. A spring winding device comprising a support, a shaft rotatably mounted therein and provided with a handle, a ratchet wheel on the shaft, a pawl pivoted on the support and co-operating with said ratchet, a member projecting outwardly from the face of the support, a guard plate rotatably mounted on said member and swingable to overlie a spring wound upon the shaft, the guard plate having a slot accommodating said shaft, and means for holding the guard plate a selected distance from the support.

3. A spring winding device comprising a support, an extension carried by the support and adapted to be engaged with holding means, a shaft rotatably mounted on the support and extending at right angles thereto, a ratchet wheel carried by the shaft, a frame surrounding said shaft and disposed in spaced relation to the support and extending over the ratchet wheel, said frame coacting with the support to provide a compartment for a pawl, a stationary shaft carried by the support, a guard plate slidably mounted on the stationary shaft, said guard plate being movable over the support and having a slot for the reception of the rotatable shaft, a keeper member disposed adjacent the shaft of the guard plate, said keeper member having a plurality of recesses adapted to receive a portion of the guard plate to hold said plate in various adjusted positions, and means carried by the support for securing one end of a spring.

4. A spring winding device comprising a support, a pin projecting from the face thereof and adapted to have one end of a spring engaged thereon, a shaft journaled through the support and equipped with a handle and a lug adapted for engagement with the inner end of the spring, a ratchet on said shaft, a pawl pivoted on the support and coacting with the ratchet, a stationary shaft projecting from the support in parallel relation to said rotary shaft, a guard plate rotatably mounted on said stationary shaft and slotted for the accommodation of the rotary shaft, the guard plate being swingable to extend across the spring, and a bar projecting from the support adjacent the stationary shaft and formed with a plurality of notches within a selected one of which the guard plate may be engaged.

In testimony whereof I hereunto affix my signature.

HENRY F. LAFORTUNE.
